UNITED STATES PATENT OFFICE.

GEORGE W. HOLMES, OF COUNCIL BLUFFS, IOWA.

DOUBLE-PISTON PUMP.

SPECIFICATION forming part of Letters Patent No. 299,788, dated June 3, 1884.

Application filed August 21, 1883. (No model.)

To all whom it may concern:

Be it known that I, GEORGE W. HOLMES, of Council Bluffs, in the county of Pottawattamie and State of Iowa, have invented certain new and useful Improvements in Double-Piston Pumps; and I do hereby declare the following to be a full, clear, and exact description of the invention, such as will enable others skilled in the art to which it appertains to make and use the same.

My invention relates to an improvement in double-piston pumps, the object of the same being to provide an improved valve adapted to divide the pump-cylinder into two parts, and act as a head to both; and it consists in the parts and combinations of parts, as will be more fully described, and pointed out in the claims.

In the accompanying drawings, Figure 1 is a view in perspective of my improved pump. Fig. 2 is a view in vertical section of the same, taken through the cylinder; and Fig. 3 is a detached view of the cylinder.

A represents a pump-stock formed in the usual manner, the lower end thereof being closed for the purpose of preventing the escape of water. This stock is provided near its lower end with the opening a, which latter registers with a similar opening, b, of the cylinder C. In deep wells, I prefer to provide the opening a of the stock with a check-valve, D, of any suitable construction, to prevent the water from flowing back into the cylinder; but in comparatively shallow wells this valve is unnecessary. The cylinder C is preferably open at both ends, and is provided centrally with a seat, d, by means of which latter the cylinder is secured to the stock by bolts or any other suitable means. The central portion of this cylinder is preferably square, as shown at e, and the two opposite faces thereof are open, the opening f being for the admission of water to the cylinder, and the opening b for the passage of water from the cylinder to the pump. Within this central portion of the cylinder is pivotally secured the valve E, which latter simultaneously opens the supply for one portion of the cylinder and opens the escape for the other. The openings b and f are rectangular in shape for the purpose of forming seats for the valve E, which latter is pivotally secured nearer its outer end to the cylinder, so that the inner end, g, thereof will naturally

rest against the lower seat, h, of the opening b, and the outer end, g', against the upper seat, h', of the opening f. Thus it will be seen that the upper half of the cylinder is in communication with the stock, while the lower half thereof is open for the reception of water. This would be the position of the several parts when the pistons are descending; but after the pistons have descended and the upper portion emptied of its water, the pistons begin to ascend and the pressure of water against the under side of the valve E partly turns the said valve on its pivot until the end g thereof rests against the seat h² and the end g' against the seat h³. When the valve is in this position, the lower portion of the cylinder is open for the escape of water into the pump-stock and the upper portion open for a new supply.

As before stated, the cylinder is open at both ends, and is provided with two pistons, I, one of which moves in the upper half of the cylinder, while the other moves in the lower half, the pistons being separated from each other by the valve E. Each piston J is provided with a rod, J', the outer ends of which are secured to the cross-heads K K', while the outer ends of the latter are connected to the opposite ends of the guide-rods L. These rods rest and move in the guides m, formed integral with the cylinder, and the yoke thus formed is moved by the pitman M, the lower end of which is centrally secured to the upper cross-head, K. The handle N is pivotally secured to the pump-stock, and the upper end of the pitman is pivotally-secured to the handle, and when the latter is operated the pistons are caused to rise and descend, and consequently force a continuous stream into the stock, which issues from the spout as fast as supplied.

Having fully described my invention, what I claim as new, and desire to secure by Letters Patent, is—

1. The combination, with a pump-stock and a pump-cylinder, the latter provided with a supply-opening and a discharge-opening, the said opening being in the same horizontal plane, of the valve D, and the valve E, the latter pivoted in the cylinder between the two openings, and dividing the cylinder into two parts, and suitable pistons above and below

the valve E, all of the above parts combined and operating substantially as set forth.

2. The combination, with a pump-stock and a pump-cylinder, the latter provided with a discharge-opening and a supply-opening, the said openings being in the same horizontal plane, of a valve pivoted in the cylinder between the said openings and dividing the cylinder into two parts, and adapted to be moved so as to close the supply and open the discharge opening to one portion of the cylinder and open the supply-opening and close the discharge to the other, and suitable pistons above and below the said valve.

3. The combination, with a pump-stock, the cylinder communicating therewith and provided with a square portion, e, having the supply and discharge openings formed therein, of a pivoted valve situated within this squared portion, and operating substantially as described.

In testimony whereof I have signed this specification in the presence of two subscribing witnesses.

GEORGE W. HOLMES.
